HOWARD S. FOLKER, OF OROVILLE, CALIFORNIA, ASSIGNOR TO THE NATIONAL SAFETY APPLIANCE COMPANY, OF SAN FRANCISCO, CALIFORNIA, A CORPORATION OF CALIFORNIA.

AUTOMATIC TRAIN-STOP.

1,284,285.

Specification of Letters Patent. Patented Nov. 12, 1918.

Continuation in part of application Serial No. 118,980, filed September 8, 1916. This application filed June 23, 1917. Serial No. 176,552.

To all whom it may concern:

Be it known that I, HOWARD S. FOLKER, of the city of Oroville, county of Butte, State of California, have invented certain new and useful Improvements in Automatic Train-Stop, of which the following is a specification.

This application is a continuation in part of my prior application Serial No. 118,980, filed September 8, 1916, for automatic train stops and consists essentially in an improved and simplified construction of the various parts going to make up what is commonly called the train stop.

15 The invention disclosed in this present application relates to an improved valve structure which valve is to be automatically operated by differences of fluid pressure controlled by any suitable means. In the particular instance shown it is controlled by an electro-pneumatic vent valve which is specifically described in my aforesaid co-pending application.

20 The invention is designed particularly to be used for automatically applying the air brakes of railway trains. The venting of a portion of the fluid pressure in a certain chamber of the valve mechanism will cause the air brake applying mechanism or train 25 stop to operate, giving either a service or emergency application of the brakes according to the class of train service in which it is to be used.

The invention hereinafter described may 30 be assumed to be constructed so that the train stop valve mechanism will give a service application of the brakes, but in order to adapt it to give an emergency application of the brakes, it is only necessary to substitute for 35 certain of the ports and passages, similar ports or passages having greater areas or capacities, all of which will be more particularly hereinafter described.

One of the objects of the invention is to 40 so construct a valve mechanism having a minimum number of parts without impairing its efficiency, so that it will be simple in construction and positive in its operation.

Another object is to so construct the valve 45 mechanism that it may be easily assembled and quickly dismantled and replaced without disconnecting any of the air or fluid pipes.

Another object is to so construct the valve

operating piston that it will perform the 55 combined functions of the valve operating piston and the diaphragm valve mechanism of my above mentioned application.

Another object is to provide a structure by means of which the valve operating piston 60 may be manually returned to its normal position regardless of the prevailing fluid pressures.

Another object is to provide a simplified construction by means of which all the parts 65 are readily accessible for the purposes of examination and repair, all as will be herein-after fully set forth.

Another object is to provide a means for rendering inoperative the valve mechanism 70 and parts operated thereby.

Other objects will appear from the following specification and claims.

Referring to the drawings, in which the same reference characters indicate the same 75 parts in the several views:

Figure 1 is a conventional diagrammatic view showing my improved train stop structure operatively connected to the engineer's automatic brake valve, main reservoir, electro-pneumatic valve and the brake pipe.

Fig. 2 is a central longitudinal sectional view with some parts in elevation and others broken away, of my improved train stop with all the moving parts in normal position.

Fig. 3 is a similar view showing the moving parts in the position which they assume upon the automatic application of the brakes.

Fig. 4 is a plan view of the connection 80 flange and the train stop secured thereto.

The part marked 10 is the main connection flange into which all the pipe connections lead and it is provided with a flat surface on one side to which the main valve body 11 is 85 bolted with suitable bolts 12. A gasket 13 is inserted therebetween so as to make an air tight joint, thus insuring against leakage between the several air passages.

The valve body 11 contains a valve 14 100 which for clearness will be designated as the "non release" valve. This valve 14 is located between the brake pipe 15 and the usual engineer's automatic brake valve 16 which is of the flat rotary type having many 105 ports, the interior construction of which it is not necessary to show, as it is readily understood in this art.

- The valve body 11 is provided with chambers 17 and 18 separated by a wall 19 in which a valve seat 20 is provided, the said valve seat being so situated as to coöperate 5 with the non-release valve 14, which valve is secured to a valve stem 21. The bottom end of said valve stem 21 projects through a perforated web 22 into the cylindrical chamber 23.
- 10 To the lower end of the valve stem 21 is removably secured a flat disk valve 24 by means of a screw 25, and said disk valve is provided with leather or any other suitable packing material 26, as shown.
- 15 A piston 30 operates in the cylindrical chamber 23 the walls of which are integrally cast with the walls of the valve body 11. The valve 24 which is secured to the lower end of the valve stem 21 is normally 20 closed, the upward pressure beneath the piston and the compression spring 32 coöperating to secure a firm seating of the valve upon the valve seat 31 formed in the top portion of the piston 30. The piston 30 is provided with packing leathers or any other suitable means of making air tight joints between the piston and the cylinder walls at each end of the piston, all as clearly 25 shown in the drawing.
- 30 A port 33 is provided in the wall of the cylinder 23 at a point midway between each end flange of the said piston 30, which port will be called the brake pipe service exhaust port.
- 35 The piston 30 is of the composite type and consists essentially of three parts, the central part 35 of which is spool shaped and bored out to receive the shank 36 of a cylindrical head piece 37.
- 40 Depending from the shank 36 is a screw threaded stem 38 to which is removably secured a head 39 for the lower end of the middle portion 35. A lock nut 40 is provided on the lower end of the screw threaded stem 38 to securely lock the parts in place. The central portion 35 of the piston is provided with flanges at each end which form between them a concentric or annular chamber 41 which is in communication with the port 33 at all times.
- 45 The valve seat 31 for the valve 24 is centrally located on the top of the piston head 37 and it is concentric with a perpendicular passage or port 42, the lower end of which connects into radial ports 43, which latter ports register with ports 44 in the wall of the central portion 35 of the piston 30. The ports 43 are intersected by an annular groove 45 to insure communication between 50 the ports 44 at all times; that is without regard to the respective angular positions into which they may be turned.
- 55 The packing leathers or cup washers hereinabove referred to, are clamped respectively between the upper and lower

heads 37 and 39 and the flanges of the spool shaped member 30.

It will thus be seen that when the head 39 is screwed onto the screw threaded portion 38, the members 37, 30 and 39 and the washers will be clamped together. As clearly shown in Figs. 2 and 3, the construction is such that the packing rings or cup washers will be held in such position that when all the parts are clamped together as above 75 mentioned, air tight joints will be formed between the cylinder wall and the packing leathers.

The main reservoir M is so connected that air will flow to the main connection flange 80 10 by suitable pipe and fittings 50, thence through a restricted port 51 of fixed capacity, into the passage 52 and into the perpendicular passage 53, thence into the chamber 54 building up a pressure therein. The 85 chamber 54 is also connected to an electro-pneumatic vent valve V by the passage 53, pipe 55 and pipe 56.

The electro-pneumatic vent valve V is assumed to be in normal position with the 90 electro-magnet 60 energized and the armature 61 in contact with the magnet. When the armature is in this position the air valve 62 is closed on its seat 63.

As clearly described in my co-pending application referred to above, the deenergizing of the magnet 60 permits the armature 61 to drop, carrying the valve 62 away from its seat 63 and allowing the air pressure in the chamber 54 to escape to the atmosphere 100 through the whistle 65.

The brake pipe pressure flowing through the supply pipe 70 leading from the engineer's automatic brake valve 16 to the chamber 17, then passes by the normally open valve 14, which is held off its seat 20 by pressure beneath the piston 30, into the chamber 18, thence into a chamber 23 by way of the air passages 23'. When, however, the pressure is relieved below the piston 30, due to the opening of the valve 62, the piston 30 is forced downward by the pressure of the air in the brake pipe which has free access to the upper surface of the piston through the passages 23'; thus permitting the valve 14 to close and interrupt the flow of air through the brake pipe to the brake mechanism.

In order that access may be readily had to the piston 30 and valve 24, a removable cylinder head 71 is provided which is securely and removably held in place by suitable screw studs 72 and nuts 73, making an air tight joint against the flange 74 projecting from the cylinder walls.

The valve stem 21 and valve 14 secured thereto can be removed from the body 11 by unscrewing a flange union nut 75 and removing the guide plug 76 for this purpose.

When the cylinder head 71 is removed 130

and the piston 30 is taken out of its cylinder 23, the valve 24 is accessible so that it may be unscrewed from the lower end of the valve stem 21. The valve stem 21 and valve 5 14 may then be removed from the body upon the removal of the union nut 75 and the guide plug 76.

A screw threaded plug 80 is provided in the cylinder head 71 at one end with a hand 10 wheel 81, and at the other end with a flange head 82. Packing gaskets 83 and 83' are provided to insure air tight joints when the stud 80 is screwed to either of its extreme positions.

15 In the event that the pipe supplying the chamber 54 should become broken, or for any other reason the supply of fluid pressure to the chamber 54 should be stopped the piston 30 will become inoperative, and I 20 am therefore enabled by the construction just described to quickly replace the piston and the parts operated thereby into normal position by turning the hand wheel 81 of the stud so that the stud will be screwed 25 into the chamber 54, forcing the piston and co-working parts into normal position regardless of the air pressure.

The hand wheel is normally rendered inoperative by means of a seal as shown which 30 obviously must be broken before the hand wheel 81 can be turned.

To adapt the above described train stop valve mechanism so that it may be effective to give an emergency application of the 35 brakes as above referred to, it is necessary only to substitute for the piston 30 a similar piston having ports 42, 43 and 44 of greater area or capacity. It follows, of course, that in substituting for the port 42 40 another port of greater capacity, that the valve 24 and valve seat 31 must also be relatively enlarged.

The operation is as follows: All the parts 45 of the valve mechanism are assumed to move into normal position as the fluid pressure is applied. As the pressure builds up in the chamber 54 it forces the piston 30 upward into the chamber 23, thus closing the valve 24 against its seat 31. The piston 30 then 50 forces the valve 24, the valve stem 21 and valve 14 upward against the pressure of the spring 32. The brake pipe pressure flowing through the supply pipe 70 leading from the engineer's automatic brake valve 16 to the 55 chamber 17, then passes by the valve 14, which is off its seat 20, into the chamber 18 and then through the air passage 23' into the chamber 23. This pressure being less than that in the chamber 54 does not cause any 60 movement of the piston 30. At the same time, air pressure from the chamber 18 also flows through the passage 15' to the brake pipe 15 building up pressure therein. The pressure in the brake pipe varies at times, 65 but is normally less than the main reservoir

pressure, but never more, the variation therein being controlled by the engineer's automatic brake valve 16.

While the above described construction forms an efficient installation, it is to be 70 noted that the parts shown are merely illustrative and are not to be interpreted in a limiting sense.

Having now described my invention, what I claim as new and desire to secure by Letters Patent is:

1. In an automatic train stop device for use with an air brake system having a brake pipe through which air may flow to and from suitable air operated brake mechanism; a normally open valve adapted to interrupt the flow of air through said brake pipe toward said brake mechanism; a cylinder; a piston movable within said cylinder and operatively associated with said valve 80 to hold the same in its normally open condition, and one end of which piston is subjected to the pressure of the air within said brake pipe; a passage extending through said piston and discharging into the external atmosphere, and through which air 85 may flow from said brake pipe; a normally closed valve for controlling the flow of air through said passage; a passage leading from a source of air under pressure into the 90 said cylinder whereby the other end of said piston is subjected to air under pressure, to thereby hold said first mentioned valve in its normally open condition; means for relieving the pressure of the air in the last 95 mentioned end of said cylinder to thereby permit said piston to move and said first mentioned valve to close; and means whereby said second mentioned valve is opened to thereby permit a flow of air from 100 said brake pipe through the passage aforesaid, when the pressure in the second mentioned end of said cylinder is relieved.

2. In an automatic train stop device for use with an air brake system having a brake 110 pipe through which air may flow to and from suitable air operated brake mechanism; a normally open valve adapted to interrupt the flow of air through said brake pipe toward said brake mechanism; a cylinder; a piston movable within said cylinder and operatively associated with said valve 115 to hold the same in its normally open condition, and the upper end of which piston is subjected to the pressure of the air within said brake pipe; an exhaust port provided in the wall of said cylinder and located between the ends of said piston; a passage extending through said piston and through which air may flow from said brake pipe 120 through said exhaust port and to the external atmosphere; a valve connected with and partaking of the movement of said first mentioned valve and adapted to control the flow of air through said passage; a passage 125 130

leading from a source of air under pressure into the lower end of said cylinder whereby the lower end of said piston is subjected to air under pressure, to thereby hold said first 5 mentioned valve in its normally open condition; and means for relieving the pressure of the air in the lower end of said cylinder to thereby permit said piston to move downwardly therein, and said first mentioned valve to close.

3. In an automatic train stop device for use with an air brake system having a brake pipe through which air may flow to and from suitable air operated brake mechanism; a 15 normally open valve adapted to interrupt the flow of air through said brake pipe toward said brake mechanism, and to permit a free flow of air in the reverse direction; a cylinder; a piston movable within said 20 cylinder and operatively associated with said valve to hold the same in its normally open condition, and the upper end of which piston is subjected to the pressure of the air within said brake pipe; an exhaust port 25 provided in the wall of said cylinder; a passage extending through said piston and through which air may flow from said brake pipe through said exhaust port and to the external atmosphere; a valve connected with 30 and partaking of the movement of said first mentioned valve and adapted to control the flow of air through said passage; a passage leading from a source of air under pressure into the lower end of said cylinder 35 whereby the lower end of said piston is subjected to air under pressure, to thereby hold said first mentioned valve in its normally open condition; and means for relieving the pressure of the air in the lower end of 40 said cylinder to thereby permit said piston to move downwardly therein, and said first mentioned valve to close.

4. In an automatic train stop device for use with an air brake system having a brake 45 pipe through which air may flow to and from suitable air operated brake mechanism; a normally open valve adapted to interrupt the flow of air through said brake pipe toward said brake mechanism, and to 50 permit a free flow of air in a reverse direction; a movable member operatively associated with said valve, one side of said member being acted upon by the air in said brake pipe in a manner tending to close said 55 valve, and the other side of said member being acted upon by air under pressure in such a way as to move said valve into and hold the same in its normal open condition; the passage through which air may flow 60 from said brake pipe to the external atmosphere; a valve associated with and controlled by said movable member, and which valve is adapted to control the flow of air through said passage; and means for relieving the pressure of the air acting upon 65

the second mentioned side and said movable member to thereby permit said member to be moved by the pressure of the air within said brake pipe, and said first mentioned valve to close.

5. In an automatic train stop device for use with an air brake system having a brake pipe through which air may flow to and from suitable air operated brake mechanism; a normally open valve adapted to interrupt the flow of air through said brake pipe toward said brake mechanism, and which valve is provided with a depending stem; a cylinder; a piston movable within said cylinder and adapted to operate through 70 said stem to hold said valve in its normally open condition, and the upper end of which piston is subjected to the pressure of the air in said brake pipe; an exhaust port; a passage extending through the upper surface of said piston and through which passage air may flow from said brake pipe to and through said exhaust port to the external atmosphere; a valve secured to the lower end of said valve stem and adapted 75 to normally interrupt the flow of air through the passage aforesaid; a passage leading from a source of air under pressure into the lower end of said cylinder whereby the lower end of said piston is subjected to 80 air under pressure to thereby hold said first mentioned valve in its normally open condition; and means for relieving the pressure of the air in the lower end of said cylinder to thereby permit said piston to move downwardly therein, and said first 85 mentioned valve to close.

6. In an automatic train stop device for use with an air brake system having a brake pipe through which air may flow to and from suitable air operated brake mechanism; a valve seat past which the air flowing in said brake pipe flows; a puppet valve adapted to seat upon said seat to thereby interrupt the flow of air toward said brake 90 mechanism, and to move away from its seat to permit a flow of air in a reverse direction; a stem depending from said valve; a cylinder; a piston movable within said cylinder and operatively connected with said valve 95 through said stem to normally hold said valve off its seat, and the upper end of which piston is subjected to the pressure of the air in said brake pipe; an exhaust port; a passage extending through said piston and communicating with said exhaust port, and through which passage air may flow from said brake pipe to the external atmosphere; a valve carried by the lower end of said valve stem and adapted to normally seat 100 upon said piston and interrupt the flow of air through the passage aforesaid; a passage leading from a source of air under pressure into the lower end of said cylinder 105 whereby the lower end of said piston is 110

115

120

125

- subjected to air under pressure, to thereby hold said first mentioned valve off its seat; and means for relieving the pressure of the air in the lower end of said cylinder to thereby permit said piston to move downwardly therein, and said first mentioned valve to move on to its seat.
7. In an automatic train stop device for use with an air brake system having a brake pipe through which air may flow to and from suitable air operated brake mechanism; a valve seat past which the air flowing in said brake pipe flows; a puppet valve adapted to seat upon said seat to thereby interrupt the flow of air toward said brake mechanism, and to move away from its seat to permit a flow of air in a reverse direction; a stem depending from said valve; a cylinder; a piston movable within said cylinder and operatively connected with said valve through said stem to normally hold said valve off its seat, and the upper end of which piston is subjected to the pressure of the air in said brake pipe; an exhaust port provided in the wall of said cylinder, and located between the ends of said piston; a passage extending through the upper surface of said piston and communicating with said exhaust port, and through which passage air may flow from said brake pipe to the external atmosphere; a valve carried by the lower end of said valve stem and adapted to normally seat upon the upper surface of said piston and interrupt the flow of air through the passage aforesaid; a passage leading from a source of air under pressure into the lower end of said cylinder whereby the lower end of said piston is subjected to air under pressure, to thereby hold said first mentioned valve off its seat; and means for relieving the pressure of the air in the lower end of said cylinder to thereby permit said piston to move downwardly therein, and said first mentioned valve to move on to its seat.
8. In an automatic train stop device for use with an air brake system having a brake pipe through which air may flow to and from suitable air operated brake mechanism; a valve seat past which the air flowing in said brake pipe flows; a puppet valve adapted to seat upon said seat to thereby interrupt the flow of air toward said brake mechanism, and to move away from its seat to permit a flow of air in a reverse direction; a stem depending from said valve; a cylinder; a piston movable within said cylinder and acting through said stem to normally hold said valve off its seat, and the upper end of which piston is subjected to the pressure of the air in said brake pipe; a passage extending through said piston and through which passage air may flow from said brake pipe to the external atmosphere; a valve carried by said valve stem
- and adapted to normally interrupt the flow of air through the passage aforesaid; a passage leading from a source of air under pressure into the lower end of said cylinder whereby the lower end of said piston is subjected to air under pressure, to thereby hold said first mentioned valve off its seat; and means for relieving the pressure of the air in the lower end of said cylinder to thereby permit said piston to move downwardly therein, and said first mentioned valve to move on to its seat.
9. In an automatic train stop device for use with an air brake system having a brake pipe through which air may flow to and from suitable air operated brake mechanism; a valve seat past which the air flowing in said brake pipe flows; a puppet valve adapted to seat upon said seat to thereby interrupt the flow of air toward said brake mechanism, and to move away from its seat to permit a flow of air in a reverse direction; a cylinder; a piston movable within said cylinder and operatively connected with said valve to normally hold the same off its seat, and the upper end of which piston is subjected to the pressure of the air in said brake pipe; a passage through which air may flow from said brake pipe to the external atmosphere; a normally closed valve with which said first mentioned valve is operatively connected, and which valve is adapted to control the flow of air from said brake pipe through the passage aforesaid; a passage leading from a source of air under pressure into the lower end of said cylinder whereby the lower end of said piston is subjected to air under pressure to thereby hold said first mentioned valve off its seat; and means for relieving the pressure of the air in the lower end of said cylinder to thereby permit said piston to move downwardly therein and said first mentioned valve to move on to its seat.
10. In an automatic train stop device for use with an air brake system having a brake pipe through which air may flow to and from suitable air operated brake mechanism; a valve seat past which the air flowing in said brake pipe flows; a puppet valve adapted to seat upon said seat to thereby interrupt the flow of air toward said brake mechanism, and to move away from its seat to permit a flow of air in a reverse direction; a stem depending from said valve; a cylinder; a piston movable within said cylinder and acting through said stem to normally hold said valve off its seat, and the upper end of which piston is subjected to the pressure of the air in said brake pipe; a passage through which air may flow from said brake pipe to the external atmosphere; a normally closed valve with which said valve stem is operatively connected, and which valve is adapted to control the flow

of air from said brake pipe through the passage aforesaid; a passage leading from a source of air under pressure into the lower end of said cylinder whereby the lower end 5 of said piston is subjected to air under pressure to thereby hold said first mentioned valve off its seat; and means for relieving the pressure of the air in the lower end of said cylinder to thereby permit said piston 10 to move downwardly therein, and said first mentioned valve to move on to its seat.

11. In an automatic train stop, a piston provided with an air passage therethrough, leading from one end thereof through the 15 side of the piston, and the discharge end of which passage is in communication with the atmosphere, and which passage leads from a chamber in communication with the brake pipe; means for subjecting the end of said 20 piston from which said passage leads to the pressure of the air within the brake pipe; means for subjecting the other end of said piston to a differential air pressure; a valve stem carrying a normally open non-release 25 valve, and a normally closed valve adapted to control the flow of air through the passage aforesaid extending through the piston; and means for relieving the pressure acting upon the second mentioned end of 30 said piston to thereby permit the pressure of the air in said brake pipe to move said piston and simultaneously bring about the closing of said non-release valve, and the opening of the valve which controls the passage aforesaid 35 extending through said piston.

12. In an automatic train stop, a piston provided with an air passage leading therethrough, and the ends of which passage are 40 in communication, respectively, with the brake pipe and with the external atmosphere; means for subjecting one end of said piston to the pressure of the air in said brake pipe, and for subjecting the other end 45 of said piston to a differential air pressure; a normally open non-release valve adapted

to interrupt the supply of air to said brake pipe; a normally closed valve adapted to control the flow of air from the brake pipe through the passage aforesaid and to the external atmosphere; means whereby said valves are operated by said piston to simultaneously bring about the closing of said non-release valve, and the opening of the valve which controls the passage aforesaid 55 leading through said piston; and means for relieving the pressure of the air acting upon the second mentioned end of said piston to thereby permit said piston to move and thereby bring about the closing of said non-release valve, and the opening of the valve which controls the passage through said piston.

13. In an automatic train stop, a cylinder, a composite piston having a central part 60 provided with flanges to form a chamber between the cylinder wall and the piston, said central part having a passageway leading to the said chamber, and heads removably secured to said central part, one being 65 imperforate and the other having a passageway therethrough leading to the passageway in the piston.

14. In an automatic train-stop, a cylinder, a composite piston having a central part, 70 said central part having a passage therethrough, a head removably secured to said piston provided with a passage co-acting with said first mentioned passage, a chamber formed between said central portion and 75 head portion to permit the communication of the several passages at all times, irrespective of the angular positions of the said piston parts.

In witness whereof I have hereunto set my 85 hand at Oroville, county of Butte, and State of California, this 13th day of June 1917.

HOWARD S. FOLKER.
